UNITED STATES PATENT OFFICE.

JOHN C. SPEAKER, OF MAGNOLIA, OHIO.

RAILROAD-TIE.

No. 867,435.

Specification of Letters Patent.

Patented Oct. 1, 1907.

Application filed February 18, 1907. Serial No. 358,140.

To all whom it may concern:

— Be it known that I, JOHN C. SPEAKER, a citizen of the United States, residing at Magnolia, in the county of Stark and State of Ohio, have invented certain new and useful Improvements in Railroad-Ties, of which the following is a specification, reference being had therein to the accompanying drawing.

My invention relates to improvements in railroad cross ties constructed of plastic material, and it consists of the novel construction, combination and arrangement of parts hereinafter described and claimed.

The object of the invention is to provide a tie of this character which may be produced at a small cost, which will be strong and durable in use, and upon which the track rails may be readily fastened.

The above and other objects, which will appear as the nature of the invention is better understood, are accomplished by the improved construction illustrated in the accompanying drawings, in which

20 Figure 1 is a perspective view of one of my improved cross ties, showing one of the track rails secured thereon; Fig. 2 is a vertical longitudinal section of the tie; Fig. 3 is a transverse section taken on the plane indicated by the line 3—3 in Fig. 2; and Fig. 4 is a perspective view of one of the metallic reinforcing plates or members of the tie.

My improved railway cross tie comprises a rectangular body 1 molded of concrete or other suitable plastic material and having in its top adjacent to its ends transversely extending seats 2, the walls 3 of which are undercut so that said seats are of dove-tail shape. These seats are adapted to receive wooden blocks 4 upon the tops of which are secured by spikes or other suitable fastenings 5 the track rails 6. The blocks 4 correspond 35 in shape to the transverse grooves or seats 2, that is their side edges are beveled upwardly and inwardly so that the blocks when driven laterally or transversely of the tie and into said seats, will be effectively retained therein.

40 It will be noted upon reference to the drawing that the blocks 4 are thicker or higher than the depth of the seats 2 so that the rails will be supported in a plane above that of the top of the tie.

In order to strengthen the plastic body of the tie and 45 prevent it from breaking, I embed in it one or more longitudinally extending reinforcing members 7. Each of the latter is in the form of a flat metal plate arranged in an upright or vertical position in the tie and having its upper edge formed with transverse recesses or seats

50 8 of the same size and shape as the seats 2 in the tie with which seats they are adapted to register, as clearly shown in Figs. 1 and 2. The reinforcing plate 7 is entirely embedded in the body of the tie, as shown in Fig. 2, but in order to more effectively anchor it, I form 55 adjacent to the ends of said plate the longitudinally

extending slots 9 which are filled with the plastic material of the body when the tie is molded.

If desired, the reinforcing plate 7 may be strengthened and still further anchored in the tie by bending its bottom edge at right angles to provide the horizontal 60 reinforcing flange 10. When this is done, the plate 7 is of L-shape in cross section, as clearly shown in Figs. 3 and 4. The flange 10 may however be omitted when the plate 7 is of sufficient thickness to give the tie the requisite strength.

In producing the tie, a suitable mold is provided and one or more of the reinforcing plates or members 7 is supported in it with suitable form blocks arranged in the seats 8. The plastic material is then filled in the mold around the member or members 7 and the form 70 blocks which latter, of course, correspond in shape to the blocks 4. After the plastic material has set the form blocks may be removed so that the wooden blocks 4 may be driven in the seats 2 of the tie when the tie is ready for use.

From the foregoing it will be observed that my improved tie may be produced at a comparatively small cost; that it is strong and durable and not liable to be easily cracked or broken; that the track rails may be easily applied to and removed from it and that the provision of the seats 2 permits the blocks 4 to be replaced when they are worn or rotten. It will also be observed that the blocks may be replaced without removing the ties from beneath the track rails.

It is also apparent that the rectangular body 1 may 85 be formed of metal or other material and the reinforcing member 7 omitted where the material used is of such a nature as not to require reinforcement, hence I do not desire to be restricted to the exact construction and arrangement shown, as minor changes may be made without departing from the spirit of the invention or sacrificing any of its advantages.

Having thus described my invention what I claim and desire to secure by Letters Patent is:

1. A cross tie comprising a body of plastic material 95 having seats in its top for track supporting blocks, and a longitudinally extending metallic reinforcing member embedded in said body and having seats to register with the seats in said body.

2. A cross tie comprising a body of plastic material 100 formed in its top with transversely extending undercut seats and a metallic reinforcing plate embedded in the body and arranged longitudinally thereof in an upright position, the upper edge of said plate being formed with undercut seats or recesses to register with the seats in said body.

3. A cross tie comprising a body of plastic material 110 formed in its top with transversely extending dove-tail seats, a metallic reinforcing plate embedded in the body and arranged longitudinally thereof in an upright position, the upper edge of said plate being formed with dove-tail seats or recesses to register with the seats in said body and dove-tail blocks of wood driven into said seats trans-

versely of the tie and having their upper surfaces in a plane above the top of the tie for supporting track rails.

4. A cross tie comprising a body of plastic material having a seat in its top for a track supporting block and a metallic reinforcing member embedded in said body and having a seat to register with the seat in said body.

5. A cross tie comprising a body of plastic material having seats in its top for track supporting blocks and a longitudinally extending metallic reinforcing member embedded in said body and having seats to register with the seats in said body, said member also having openings for the reception of plastic material of the body, substantially as set forth.

6. A cross tie comprising a body of plastic material having seats in its top for track supporting blocks and the longitudinally extending metallic reinforcing plate 7 formed with a lateral flange 10 at its bottom and with openings 9 and seats 8, said seats being in its upper edge and adapted to register with the seats in said body, substantially as set forth.

In testimony whereof I hereunto affix my signature in presence of two witnesses.

JOHN C. SPEAKER.
